[57] CLAIM

The ornamental design for a identification tag, as shown and described.

DESCRIPTION

FIG. 1 is a top plan view of an identification tag showing my new design, with the tag shown in open condition;

FIG. 2 is a front elevational view thereof;

FIG. 3 is a bottom plan view thereof;

FIG. 4 is a rear elevational view thereof;

FIG. 5 is a left side elevational view thereof, with the tag shown in closed condition;

FIG. 6 is a right side elevational view thereof;

FIG. 7 is a top plan view thereof, with the broken lines showing for illustrative purposes only and forming no part of the claimed design;

FIG. 8 is a front elevational view thereof;

FIG. 9 is a bottom plan view thereof;

FIG. 10 is a rear elevational view thereof;

FIG. 11 is a left side elevational view thereof;

FIG. 12 is a right side elevational view thereof.
